UNITED STATES PATENT OFFICE.

HUGO SACK, OF DUSSELDORF, GERMANY; ADELHEID SACK ADMINISTRATRIX OF SAID
HUGO SACK, DECEASED.

METHOD OF MAKING CHANNEL-BARS WITH TAPERLESS FLANGES.

939,171.

Specification of Letters Patent.

Patented Nov. 2, 1909.

Application filed November 30, 1908. Serial No. 465,413.

To all whom it may concern:

Be it known that I, HUGO SACK, a subject of the Emperor of Germany, residing at Dusseldorf, Rhinen Prussia, Germany, have invented certain new and useful Improvements in Methods of Making Channel-Bars with Taperless Flanges, of which the following is a specification.

In the ship-building trade and elsewhere, channel-bars are preferred the taper of whose flanges is as small as possible. Channel-bars with taperless flanges would be most desirable, but up to the present time no practical method of producing them has been devised. If it be attempted to roll such bars by the ordinary method, employing pairs of grooved rolls, the roll-grooves must have parallel walls. The inevitable result is that the metal is so firmly pressed into the grooves that it cannot readily leave them, the flanges tearing away from the web and remaining jammed in the roll, forming collars, so that upon further use the rolls are broken.

The present invention is an improved method of rolling a channel-bar with taperless flanges.

Referring to the drawings: Figure 1 is a sectional view of a preliminary form of channel-bar; Fig. 2 is a front elevation of the adjacent portions of rolls for practicing the final step of my improved method, showing the preliminary bar in section in a transverse vertical plane in front of the rolls; and Fig. 3 is a similar view showing the finished bar in section in the plane of the roll-axes.

The preliminary channel-bar 1 is rolled in grooved rolls, the flanges 2 being taperless and all parts of the bar being of the final thickness. The web 3 is slightly curved but

the flanges are at right angles to the web. This permits the flanges to readily leave the grooves of the reducing rolls. The bar is then squared up without substantial elongation by a second set of rolls, comprising an upper roll 4 and a lower roll 5. The upper roll has a cylindrical pressure surface 6 and square shoulders 7. The lower roll has a cylindrical surface 8, of a length slightly greater than the width of the finished channel-bar; shoulders 9 in planes transverse to the axis of the roll; and outwardly-extending conical surfaces 10. The preliminary bar is fed to the rolls with its diverging flanges guided by the conical surfaces 10 of the lower roll, the lower corners of the channel-bar being supported on the cylindrical surface of the lower roll, and as it enters the pass of the roll the web is flattened down and the flanges are bent inward into parallelism, the bar assuming the final form shown in section in Fig. 3.

I claim:

The method of making channel-bars with taperless flanges, which consists in first producing a preliminary bar with a transversely-curved web and taperless marginal flanges extending from and substantially at right angles to said web, and then flattening the web and bringing the flanges into mutual parallelism by simultaneously applying pressure to the convex side of the web and to the outer faces of the flanges at points adjacent to the web.

In testimony whereof, I affix my signature in presence of two witnesses.

HUGO SACK.
